CLIFFORD E. BRE MILLER, OF CHICAGO, ILLINOIS, ASSIGNOR TO COOK LABORATORIES, INC., OF CHICAGO, ILLINOIS, A CORPORATION OF ILLINOIS

RECEPTACLE

Application filed March 28, 1928. Serial No. 264,681.

This invention relates to improvements in receptacles and among other objects, aims to provide a receptacle constructed so as to facilitate the cleansing, sterilization, and handling of the tubular glass bodies of medicament-dispensing cartridges.

In the drawings:

Fig. 1 is a perspective view of the improved receptacle with both the hinged and sliding closures partly open;

Fig. 2 is a transverse, sectional view taken on the line 2—2 of Fig. 1 with both closures in closed position;

Fig. 3 is a similar view taken on the line 3—3 of Fig. 1 with the sliding closure partly open; and

Fig. 4 is a sectional view taken on the line 4—4 of Fig. 1 and at right angles to Figs. 2 and 3.

In the manufacture of medicament-dispensing cartridges for hypodermic and other syringes, as described in certain co-pending applications, sections of glass tubing are washed and sterilized, have rubber plugs inserted in their opposite ends and are re-sterilized, before the medicament is introduced into them. As the medicament is to be injected into human tissue, it is most important that it should not be contaminated by bacteria or spores on the inner surface of the cartridges themselves, or by the atmosphere, which is always laden with dust and other bacteria-carrying agencies. Hence it is highly desirable to facilitate the handling of the glass tubes, especially after sterilization but before sealing, so that the tubes are transferred quickly from a sterilizer to a machine and into the next sterilizer, with as little exposure as possible and without handling; and it is also highly desirable that a large mass of tubes be sterilized at a time, preferably in groups of several hundred each. The present invention facilitates the grouping of the tubes for sterilization and handling, and co-operates with other machines for heat-treating the tubes, and for stoppering the tubes, as disclosed in my pending applications, Ser. Nos. 219,888 and 221,824 and filed September 16, 1927 and September 24, 1927 respectively.

Referring particularly to the drawings, the receptacle is shown as being a substantially rectangular cage with a hinged closure and a sliding closure. While the receptacle is used in different positions, during different operations, for the purpose of clearness it will be described as shown in Fig. 1, that is, with the hinged closure as the top.

Herein, the receptacle is shown as comprising substantially square upper and lower frames 10 and 11 formed of stiff wire, and held in spaced parallel relation by posts 12 and 13, formed of sheet metal or the like and secured to the frames as by brazing or the like. The posts 12 are located at the rear corners of the receptacle and are bent to form small angle bars with their vertical flanges extending along the rear and side walls, while the posts 13 are flat and are located at sides of the receptacle at the front edges thereof. The side and rear walls are herein shown as being formed of panels of non-rusting foraminous material, such as brass or bronze wire screening of punched sheet brass. The side panels 14 and 15 and the rear panel 16 are all located on the inside of the receptacle and have their marginal edges bent outwardly and around the upper and lower frames and soldered or otherwise secured thereto. The bottom of the receptacle is also formed of a panel of screening 17, the side and rear edges of which are brought under and around the corresponding portions of the lower frame 11 to which the screening is secured.

In order to provide an unobstructed opening in the front and to provide guides for a sliding closure, the front bar 18 of the lower frame 11 is offset downwardly by bending the front ends of the side bars at 19 and the corresponding front bar 20 of the upper frame 10 is offset upwardly by bending the front ends of the side bars as at 21. This permits the front edge of the bottom panel 17 to be brought over and around the front bar 18 to which it is secured.

The sliding closure 22 may be formed of non-rusting sheet metal of sufficient length to extend across the front of the receptacle from side to side and wide enough to per-

mit the upper edge thereof to be bent over and partly around the upper front bar 20 to constitute a curved flange 23 adapted to slide along the bar 20, while the lower edge is 5 similarly bent to provide a curved flange 24 of slightly greater radius to permit the same to slide along the screening on the lower front bar 18. The frictional engagement between the flanges and the rod serves to hold 10 the closure in any adjusted position along the rods.

The lid 25 for the top comprises a frame 26 of heavy wire and smaller than the frame 10 to permit it to be positioned within the 15 same. A panel of screening 27 is located on the underside of the frame 26, and has its marginal edges passing under and around the sides of the frame to which they are secured by solder or the like. The lid 25 is 20 hinged to one of the top side bars of the upper frame by hinges 28 preferably formed of strips of sheet metal bent to provide spaced parallel eyes 29 and 30 which surround the adjacent bars of the frames 25 and 10. It 25 is desirable to secure the eyes 29 to the frame 25 by brazing or the like while the eyes 30 are free to swing on the side bar of the frame 10. To retain the lid 25 in closed position, latches 31 are provided which are preferably 30 made of strips of sheet metal bent to form eyes 32, which are secured to the side bar 1 of the frame opposite to the hinges 28, and offset spring tongues 33 which snap around the adjacent side bar of the frame 10 when 35 the lid is closed. The screening in the panels 15 and 27 is cut away around the hinges 28 and the latches 32 so as not to interfere with the operation of these parts.

When the receptacle is to be used to delivered tubes therefrom, as in application Serial No. 221,824, it is positioned so that the corner between the side panel 14 and the open side defined by the bars 18 and 20 is lowermost, with the lid 25 closed and the 40 sliding closure controlling the outlet. When it is to be used as a receiving container, as in both of the above-mentioned applications, it is placed on a tiltable support with the opening between the bars 18 and 20 substantially vertical, the lid 25 in closed position, and the sliding closure open or removed. As the tubes are delivered into the receptacle from the machine, their increasing weight causes the support to rock downwardly, when 45 the open side of the receptacle is brought uppermost. When used to contain the tubes while they are being sterilized it may be in any desired position with both closures in closed position, and when the tubes are to be removed therefrom as when they are to be filled, it is positioned so that the panel 17 is lowermost, the sliding closure 22 in closed position, and the lid 25 open.

Obviously, the invention may be embodied 50 in various forms.

What is claimed is:—

1. A receptacle in the form of a parallelopiped having open-work material on four sides, a hinged closure of open-work material on the fifth side and a sliding closure on the sixth side; the interior of the receptacle being entirely unobstructed so that it may be entirely filled with glass cartridge tubes or the like.

2. A receptacle, comprising spaced, parallel rectangular frames; corner posts between the frames, holding them spaced apart; open-work material on three sides and the bottom; a sliding closure on the fourth side; and a lid of open-work material hinged at one side 75 to one of the rectangular frames and providing the top for the receptacle.

3. A receptacle in the form of a parallelopiped, comprising a pair of rectangular frames; corner posts secured between the 85 frames; walls of open-work material extending between the frames on three sides thereof, and on the inner sides of the frames; a bottom of open-work material on the outside of one of the frames; a closure for the receptacle comprising a rectangular frame somewhat smaller than the first mentioned frames to fit snugly in one of them and having open-work material secured thereto and hinged at 90 one side to the frame in which it fits; and a 95 sliding closure for the fourth side of the receptacle which is slidable over the frames.

4. An open, cage-like receptacle comprising spaced, rectangular upper and lower frames having four substantially equal sides; corner posts connecting said frames; foraminous material secured to three corresponding sides of the frames to constitute rear and side walls of the receptacle; the frame member on the fourth side of the upper frame 105 being offset upwardly and the corresponding member of the lower frame offset downwardly to form guides; a sliding closure mounted on the guides and controlling the opening therebetween; a bottom of foraminous material marginally secured to the lower frame; 110 and a lid hinged to the upper frame.

In testimony, that I claim the foregoing as my own, I have hereto affixed my signature.
